UNITED STATES PATENT OFFICE.

FRED NEWELL TILTON, OF HARTFORD, CONNECTICUT.

STEAM-GENERATOR.

939,759.

Specification of Letters Patent.

Patented Nov. 9, 1909.

Application filed October 29, 1908. Serial No. 460,017.

To all whom it may concern:

Be it known that I, FRED N. TILTON, a citizen of the United States, and a resident of Hartford, in the county of Hartford and State of Connecticut, have invented a new and Improved Steam-Generator, of which the following is a full, clear, and exact description.

The invention relates to tubular boilers having pipe coils connected in series, to form one continuous passage for the water and steam, and its object is to provide a new and improved steam generator having no sharp bends and but few and straight joints between the pipe coils, the latter being arranged to permit ready assembling and to allow convenient access to any one of the coils.

The invention consists of novel features and parts and combinations of the same, which will be more fully described herein-after and then pointed out in the claims.

A practical embodiment of the invention is represented in the accompanying drawings forming a part of this specification, in which similar characters of reference indicate corresponding parts in all the views.

Figure 1 is a plan view of the improvement, the inclosing shell being shown in section; Fig. 2 is a side elevation of the same, the shell and burner being shown in section; and Fig. 3 is a side elevation of one of the spacing blocks.

The plurality of connected pipe coils shown in the drawings, consists of a top pipe coil A, a bottom pipe coil B and a desired number of intermediate coils C, arranged one above the other and all inclosed in a shell D having an opening D' at the bottom D² for the passage of the heat from a suitable burner E, the lowermost coil being seated on the said bottom D².

The coils are held spaced apart by placing blocks F, having notches at the top and bottom to fit the pipes, and the coils are bound together by top and bottom bars G and G' connected with each other outside of the coils by bolts G², as plainly indicated in Fig. 2.

The water inlet A' for the inner end of the uppermost coil A extends between the top coil A and the next following coil C below, and the outer end of the top coil A is connected by the connection A² with the outer end of the next coil C below, but the intermediate coils C all connect at their in-

ner^rends by connections C' with the outer end of the next following intermediate coil C below, the connection extending over the top of the corresponding intermediate coil C and then down the outside thereof, to connect with the outer end of the next following intermediate coil C below. In a like manner the lowermost intermediate coil C has its inner end connected by the connection C² with the outer end of the bottom coil B, the connection C² extending on top of the lowermost intermediate coil C, and over the outer end thereof, to then merge into the outer end of the bottom coil B. The inner end of the bottom coil B terminates in the steam outlet B' which passes over the top of this bottom coil B, past the outside thereof, to then merge into a pipe B² rising within the shell D and passing through the top thereof to connect with the motor or other device in which the steam is to be utilized.

The couplings H, between the several coils are in the straight portions, as plainly indicated in Figs. 1 and 2, so that all sharp bends are prevented and the joints are but few, that is, not more than the number of coils employed.

By the arrangement desired the coils can be readily assembled and connected with each other, and convenient access can be had to any one of the coils whenever it is necessary to repair or remove any one of the coils.

It is evident that the water flowing through the coils from the top downward encounters very little resistance as sharp bends are avoided, and consequently a large amount of water can be quickly converted into steam, carried off from the lowermost coil located nearest the source of heat.

Having thus described my invention, I claim as new and desire to secure by Letters Patent:

1. A steam generator, comprising a cylindrical shell having an opening in the bottom for the passage of heat, a plurality of pipe coils arranged one above the other in said shell, the lowermost coil being seated on the bottom of the shell, the said pipe coils being connected in series, the connections extending between adjacent pipe coils, radially arranged blocks interposed between the coils to hold the same spaced apart, the said blocks having notches at the top and bottom to fit the pipes, oppositely arranged

- top and bottom bars engaging the top and bottom coils, and extending respectively above and below the corresponding outer ends of the notched blocks, and bolts extending outside of said coils and connecting the ends of the top and bottom bars with each other to bind the coils together.
2. A steam generator, comprising a top pipe coil connected at its inner end with a water supply, a bottom pipe coil having its inner end terminating in a steam outlet intermediate pipe coils, of which the uppermost has its outer end connected with the outer end of the said top pipe coil, the said intermediate coils each having its inner end connected with the outer end of the next pipe coil below, the connection passing between adjacent coils, blocks interposed between the coils, the said blocks having notches at the top and bottom to fit the pipes, oppositely arranged top and bottom bars engaging the top and bottom coils and projecting at their ends beyond the coils, and bolts extending outside of said coils and connecting the projecting ends of the top and bottom bars to bind the coils together.
3. A steam generator, comprising a top pipe coil, a bottom pipe coil, and intermediate pipe coils, a water inlet pipe extending between the top coil and the next following coil below and connected with the inner end of the top pipe coil, a connection between the outer end of the said top pipe coil and the outer end of the uppermost intermediate pipe coil, a connection between the inner end of each intermediate coil and the outer end of the next pipe coil below, the connection extending over the top of the corresponding intermediate coil and then down the outside thereof to connect with the said outer end of the next following coil below, the bottom pipe coil having its inner end terminating in a steam outlet.
4. A steam generator, comprising a top pipe coil, a bottom pipe coil and intermediate pipe coils arranged one above the other, a water inlet pipe connected with the inner end of the top pipe coil, the said water inlet pipe extending between the top coil and the next following coil below, a connection between the outer end of the said top pipe coil and the outer end of the uppermost in-

termediate pipe coil, a connection between the inner end of each intermediate pipe coil and the outer end of the next following intermediate coil, the connection extending over the top of the corresponding intermediate coil and then down the outside thereof to connect with the outer end of the next following intermediate coil below, a connection between the inner end of the lowermost intermediate coil and the outer end of the bottom pipe coil, the said connection extending on top of the lowermost intermediate coil and over the outer end thereof and merging into the said outer end of the bottom pipe coil, the bottom pipe coil having its inner end terminating in a steam outlet pipe passing over the top of the bottom coil to the outside thereof.

5. A steam generator, comprising a shell having an opening in the bottom for the passage of the heat to the interior thereof, a top pipe coil, a bottom pipe coil seated on the bottom of the shell, and intermediate pipe coils arranged one above the other and all inclosed in said shell, a water inlet pipe connected with the inner end of the top pipe coil, the said water inlet pipe extending between the top coil and the next following coil below, a connection between the outer end of the said top pipe coil and the outer end of the uppermost intermediate pipe coil, a connection between the inner end of each intermediate pipe coil and the outer end of the next following intermediate coil, the connection extending over the top of the corresponding intermediate coil and then down the outside thereof to connect with the said outer end of the next following intermediate coil below, the bottom pipe coil having its inner end terminating in a steam outlet pipe, and a connection between the inner end of the lowermost intermediate coil and the outer end of the bottom pipe coil, the said connection extending over the top of the lowermost intermediate coil and merging into the said outer end of the bottom pipe coil.

In testimony whereof I have signed my name to this specification in the presence of two subscribing witnesses.

FRED NEWELL TILTON.
